UNITED STATES PATENT OFFICE.

JOSEPHUS J. BROWN, JR., OF TROY, ILLINOIS.

ROASTING AND SMELTING FURNACE.

No. 888,582.

Specification of Letters Patent.

Patented May 26, 1908.

Application filed August 12, 1907. Serial No. 388,170.

To all whom it may concern:

Be it known that I, JOSEPHUS J. BROWN, Jr., a citizen of the United States, and resident of Troy, Illinois, have invented certain new and useful Improvements in Roasting and Smelting Furnaces, of which the following is a specification.

This invention relates to improvements in roasting and smelting furnaces and consists 10 in the novel arrangement, construction and combination of parts as will be fully herein-after described and claimed.

The object of my invention is to provide an attachment to a roasting and smelting 15 furnace whereby the material within the hearth box may be mechanically agitated and mixed.

A further object of my invention is to provide a roasting and smelting furnace with a 20 mechanical means whereby the contents of the hearth box may be thoroughly mixed without the use of hand tools, which is the present process of mixing the ore with the fire.

25 In the drawings: Figure 1 is a vertical cross sectional view of my complete invention taken on the line 1—1 of Fig. 2. Fig. 2 is a sectional view taken on the line 2—2 of Fig. 1. Fig. 3 is a detail perspective view of 30 the guide rails made use of in connection with my invention. Fig. 4 is a detail top plan view of the fork made use of to agitate the ore. Fig. 5 is a perspective view of the same.

35 In the construction of my invention I provide in connection with an ordinary roasting and smelting furnace, an agitating mechanism 6 which consists of an operating shaft 7 having a plurality of cranks 8, the said shaft 40 being mounted in bearings 9 suspended from the ceiling of the building or framework of any structure. On the end of said shaft is a gear wheel 10 with which meshes a pinion 11 driven by a pulley 12 or any suitable mechanism by which said shaft may be placed in 45 revolution.

To the cranks 8 are attached one end of the agitator bars 13, the opposite ends of said bars provided with a socket in which are 50 placed and held agitating forks 14. The cranks in the shaft are so arranged that while said shaft is revolving the agitator bars are in various locations. By this arrangement the material within the hearth box is continuously 55 being agitated by the movement of the agitators and said agitators are in such

positions that while some are entering on one side, others are submerged, some being withdrawn on the opposite side and others again in the act of entering. This operation is accomplished by the guide rails 15 which extend across the entire furnace and between said bars are placed division braces 16. Between said bars and the division braces operate the agitator bars 13. This arrangement, in connection with the cranks, is such that while the shaft is being operated, the agitator bars will assume various positions, the lowest end or that part to which the fork is attached will have a kind of a circular motion permitting said fork to enter on one side of the hearth box, pass down through the material and out on the opposite side completely stirring up the ore and other material within the hearth box.

17 indicates the hearth box; 18, a cast iron water jacket; 19, the nozzles for the admission of the air blast from the blast entry 20. This construction of the furnace is not new and I desire to make no claims on its construction.

On the top of the furnace I place a housing 21 which encircles the entire agitating mechanism extending downwardly on the front side to a height sufficient to permit the insertion of the material into the hearth box over the work shelf 22. The object and purpose of the housing 21 is to catch the fumes, gases and smoke and permit the same to be expelled through the outlet 23. At one corner 90 of the hearth I provide an opening or small depression 24 through which the molten ore may flow out into a receptacle placed there to receive the same.

I do not desire to limit myself to the precise construction of operating mechanism for placing the agitators in operation; I may use a cam mechanism or other manner of construction whereby the agitators may be operated to enter the hearth box at the front end, 100 pass through the same and be removed at the rear end for mixing up the contents while the smelting process is in action.

In common practice the material within the hearth box is mixed by men using crowbars or other tools. This slow and clumsy method is dispensed with by providing mechanical agitators.

Having fully described my invention, what I claim is:

1. A device of the class described comprising a plurality of agitators in combination

with a roasting and smelting furnace, said agitators arranged to alternately dip into the hearth of the furnace to mix the material therein, and means for operating the agitators, substantially as specified.

2. A device of the class described comprising a roasting and smelting furnace; a plurality of agitators mounted above the smelting furnace; forks carried on the end of the agitators to communicate with the material within the hearth of the roasting and smelting furnace for mixing the material therein, and a means for placing the agitators in operation, substantially as specified.

15 3. A roasting and smelting furnace comprising a hearth box; a housing mounted over the hearth box; a plurality of agitators

located within the housing; means provided on the lower end of the agitators to contact with the material within the hearth box for 20 agitating the same, and a means connected to the upper end of the agitators for placing the same in operation to provide a circular movement to the bottom end of the agitators so as to enter, pass through and pass out of 25 the material within the hearth, substantially as specified.

In testimony whereof, I have signed my name to this specification, in presence of two subscribing witnesses.

JOSEPHUS J. BROWN, JR.
